UNITED STATES PATENT OFFICE.

JOHN D. KOOYMAN, OF SALT LAKE CITY, UTAH.

AUTOMATIC ELEVATOR-STOP.

1,136,144.

Specification of Letters Patent. Patented Apr. 20, 1915.

Application filed April 22, 1913. Serial No. 762,901.

To all whom it may concern:

Be it known that I, JOHN D. KOOYMAN, subject of the Queen of the Netherlands, residing at Salt Lake City, in the county of Salt Lake and State of Utah, have invented certain new and useful Improvements in Automatic Elevator-Stops, of which the following is a specification.

My invention relates to new and useful improvements in safety devices for elevators and the object of my invention is to provide a trip mechanism which will automatically cut off the power and therefore stop an ascending elevator if any object carried by the elevator car should project therefrom in such a manner as to strike beneath the floor which the car is approaching.

It often happens that elevators, and particularly freight elevators, operating in an open well, are so carelessly loaded that a packing box or other object carried by the elevator projects a sufficient distance beyond the elevator to strike beneath the floor of an upper story, during the upward movement of the car thereby blocking further movement of the car. Under the present circumstances, if such an occurrence takes place, the result is a burning out of the fuse through which the motive current passes or a breaking of the elevator cable or other injury to the lifting mechanism of the elevator.

The object of my invention is to provide an automatic trip for attachment to elevator wells which will overcome this difficulty.

A further object of my invention is to provide a trip in the elevator well at each floor and so arranged that all of the trips are operatively connected to the power controlling cable of the elevator. And a still further object of my invention is to construct the trips in the form of an apron or shield so that when the floor of the elevator has passed above the lower portion of the trip it will absolutely be impossible for any object to later move outwardly between the trip and floor to obstruct the passage of the elevator.

With these and other objects in view, my invention will be more fully described, illustrated in the accompanying drawing, and then specifically pointed out in the claim which is attached to and forms a part of this application.

In the drawing: Figure 1 is a fragmentary sectional view showing a conventional

form of elevator well and car in elevation; Fig. 2 is a sectional view on the line 2—2 of Fig. 1.

Corresponding and like parts are referred to in the following description and indicated in all the views of the drawing by the same reference characters.

In order to insure a clear and complete understanding of my safety appliance I have illustrated the same in connection with an elevator structure of conventional type, the car such as is generally employed in freight elevators being indicated at 10 and mounted for movement in an elevator well 11 including spaced guides 11 and 12, this car being raised and lowered by means of a lifting cable 13 adapted to be wound about a sheave 14 mounted at the top of the well or at any other suitable and convenient point. The lifting mechanism is governed by a control mechanism indicated as a whole by the numeral 15 and of any suitable type, this mechanism being in turn actuated and controlled by the power controlling cable 16 which forms an endless belt about a pulley 17 carried by the control mechanism and a pulley 18 mounted at the bottom of the well, one side of this cable belt passing through the car and being adapted to be pulled up or down to operate the control mechanism and so cause the elevator to move. This control cable operates in the usual manner, that is if pulled upwardly the cable will actuate the control mechanism to stop the movement of the elevator. It will therefore be apparent that if trip devices are positioned at each floor of the elevator well and operatively connected to this cable in such a manner that when engaged and moved they will pull upwardly on the cable the protection desired will be afforded.

The elevator well illustrated is of the usual freight type open at its front and back for more convenient handling of the freight and for this reason two trips are employed at each floor one at the front and one at the back. Each of these trips includes levers 19 pivoted intermediate their length upon downwardly depending brackets 20 carried by the floor adjacent the sides of the well, the outer ends of these levers being connected by a rod 21. A plate of sheet metal 22 has its lower edge curled about the rod 21 and riveted to secure the plate to the rod and the body portion of this plate extends upwardly and outwardly to rest against the edge of

the floor in front of the well, as shown. Stop arms 23 carried by the floor or any suitable portion of the well extend in the path of the inner ends of the levers to limit 5 their movement and hold the levers in such a manner that the lower edge or rod inclosing portion of the trip shield or apron extends a considerable distance below the floor and just clear of the path of the elevator 10 which passes between the levers and between the trip shields or aprons.

A cable 24 is secured by one end to the inner end of one of the levers of the lowermost trip device at the front of the elevator and 15 through the corresponding levers of all trip devices at the various floors at the front of the elevator and by its upper end to the inner arm of a lever 25 which is pivoted intermediate its length upon a bracket 26. In 20 like manner a cable 27 connects the free ends of corresponding levers of the trip devices at the rear of the elevator with one arm of a bell crank lever 28 also carried by a bracket 29 at the upper end of the elevator 25 well. The free arm of this latter lever 28 is connected by a rod 30 with one arm of a bell crank lever 31 which is pivoted upon the bracket 26 with its other arm extending in parallel spaced relation to the outer end of 30 the lever 25. The free ends of both the levers 25 and 31 terminate in eyes 32 through which the inner section of the control cable 16 passes. A pair of adjustable stops 33 are secured upon the inner section of the control 35 cable in such a position that when the trips are in operative position and the free ends of the levers 25 and 31 inclined downwardly as shown in Fig. 2, these stops will rest upon the eyes of the adjacent levers. Under these 40 conditions it will be apparent that any upward swinging of the outer end of any one of the trips will act either through the cable 24 and lever 25 or through the cable 27 and levers 28 and 31 upon the control cable 16 to 45 pull the same upwardly and shut off the power from the raising mechanism of the elevator. The weight of the shield plates or 50 aprons of the trips is sufficient to hold the trips in active position while the levers 25 and 28 may be normally held in position by helical springs 34 and 35, respectively, or counterweighted for the same purpose as preferred.

The operation of my safety appliance will 55 be readily understood from the foregoing description when taken in connection with

the drawing, it being clear that any object carried by the car and extending beyond the edge of the same at the front or rear will engage against the lower portion of the trip 60 to swing the same upwardly and act through the trip cable to operate the control cable and shut off the power. The shields or aprons 22 may be omitted if preferred without affecting the operativeness of the appliance, but these shields, if employed, will absolutely prevent accident which might otherwise happen through the outward movement of some object in the car during ascent of the car and after it had passed a trip and before 70 it had reached the adjacent floor. If the shields are employed, it will be apparent that no such outward movement of the object would be possible as it would strike against the inner face of the shield or apron and 75 be held in place.

It will of course be understood that I do not wish in any way to limit myself to the specific details of construction illustrated in the drawing and described in the above 80 specification or to the application of the safety appliance to the particular type of elevator therein shown and described, as various minor changes, within the scope of the appended claim, may be made at any time, 85 without in the slightest degree departing from the spirit of my invention.

The stops 33 are preferably spaced apart so that either lever 25 or 31 may be swung to stop the car without affecting the other 90 and consequently without having to raise the trips at the opposite side of the well.

Having thus described the invention, what is claimed as new is:

The combination with an elevator well 95 and a cage mounted for travel therein and a power controlling cable, of tripping means arranged below each floor of the well, levers having co-operative engagement with the power controlling cable at spaced points, the 100 tripping means at each floor of the well being arranged at the opposite sides of the opening in the floor, and connection between each of the tripping means and one of the levers for actuating the lever when the respective means is tripped.

In testimony whereof I affix my signature in presence of two witnesses.

JOHN D. KOOYMAN. [L. S.]
